UNITED STATES PATENT OFFICE.

FRANK S. BARKELEW, OF LOS ANGELES, CALIFORNIA.

CASING-ELEVATOR.

960,239.

Specification of Letters Patent. Patented May 31, 1910.

Application filed December 17, 1908. Serial No. 487,948.

To all whom it may concern:

Be it known that I, FRANK S. BARKELEW, a citizen of the United States, residing at Los Angeles, in the county of Los Angeles 5 and State of California, have invented new and useful Improvements in Casing-Elevators, of which the following is a specification.

The present invention relates to a casing 10 elevator particularly adapted to well work where there is but one elevator used, a separate device being utilized to support the casing while the elevator is being removed and placed on the successive joint for placement in, or removal from, the well. This 15 supporting device, termed a spider, is adapted to grip the casing and hold it at any point and does not necessarily have to be placed under a collar on the casing in order to support it. In the usual case the spider is 20 placed under the derrick floor and is operated to grip the casing at any desired point. The elevator is then placed under the collar on the successive joint of casing and the 25 joint screwed into the casing supported by the spider. The spider is then loosened and the casing lowered, being caught again and held by the spider when the top of the upper joint comes to a convenient position above 30 the derrick floor. The elevator is then removed by slipping over the top of the casing and the above operation is repeated to place the next joint in connection with the string 35 already in the well.

The present invention consists in a construction which may be put on and taken off the casing over the end thereof. On this account it is constructed with a body portion of a continuous, integral ring in contradistinction to the style of elevators now in use 40 and which are necessarily made in two hinged halves with a separate and distinct bail on each half. The present construction has only one bail as the rigid ring allows of 45 the use of such.

As the invention consists in the before explained use of a solid ring adapted to be taken off over the end of the casing, in combination with a single bail, the means for 50 securing the casing in the elevator may be varied to suit the particular needs of any individual case. There are differing conditions which must be met in the construction of a successful elevator and these are met in the 55 present construction by the use of differing devices for gripping and supporting the cas-

ing. In the drawings several forms are shown, one form being more readily adaptable to some conditions than the others.

There are two distinct forms of devices 60 possible for engaging with the casing and these are those which grip the casing itself with a frictional or semi-frictional engagement, and those which depend upon the presence of a collar on the casing against 65 which the supporting means bears. The first form has the advantage of not injuring the collar in any way and also of not depending on the collar to hold the whole weight of the casing below. It also has the 70 distinct advantage that it can be applied to the casing at any point along its length without reference to the presence of a collar. By this arrangement the casing can be supported at any desired elevation from a point on the 75 derrick floor or underneath the same, this constituting a distinct advantage in drilling operations. The second form has the advantage of not tending to crush the casing in any manner, the support being on and under 80 the casing collar. This form is the easier to apply and to remove from the casing and also has the advantage of extreme simplicity. In this form a lock has been applied to the catch mechanism to hold it against 85 disengagement from the casing except when such disengagement is desired and is effected by manual means.

In pursuance of the above outlined plan of the invention there are three distinct 90 forms of supporting devices illustrated in the accompanying drawings, in which:

Figure 1 is a vertical section of one form of the complete elevator with the casing therein. Fig. 2 is a horizontal cross section 95 taken on line 2—2 of Fig. 1. Fig. 3 is a sectional plan view of a second form of the complete elevator. Fig. 4 is a vertical section taken on line 4—4 of Fig. 3. Fig. 5 is a sectional plan view of a third form of the 100 invention.

Referring particularly to Figs. 1 and 2, 5 designates the body portion or ring of the elevator illustrated around casing 6 beneath collar 7. Ring 5 is formed with its internal 105 opening 8 of sufficiently large diameter to easily slip over the collar of the casing, a bearing portion 9 being formed on one side with a radius corresponding to the radius of the casing so that a line of support of some 110 length is provided under the collar. The center of this bearing portion is preferably

non-coincident with the center of the ring, but this is not essential; being only for efficiency of design.

On the outside of the ring and opposite the bearing portion 9 a bracket 10 is formed. To this bracket a catch member 11 is pivoted at 12, the member extending inwardly to engage with the casing. For this purpose it is provided with a circular inner end which 10 fits snugly against the casing. As illustrated in Fig. 1 the collar rests upon bearing portion 9 at one side and on catch member 11 on the other. The catch member may be pivoted in other manners, the requisite point 15 being that it shall swing to and from the casing; but its preferred pivoting is shown in the drawings.

It will be seen that it is impossible to move the catch member upwardly and outwardly so as to disengage the casing while 20 the collar rests on the member. There are times, however, when the casing is supported temporarily by other means, such as the sticking of the lower parts in the well, and it is evident that if the elevator were then 25 moved downwardly on the casing there would be a frictional tendency to raise the catch member. To prevent this a lock has been added to the catch member. Bracket 30 10 is extended above the top of the catch member as at 13 and the outer end of pivoted lock member 14 rests against it. The lock member is pivoted at 15 to the catch member and is provided with a handle 16. 35 An upward pull on the handle will first move the end of the lock member out of engagement with the portion 13 of the bracket. A further pull will move the catch member upwardly and outwardly to disengage the 40 casing which may then be slipped out of the elevator through the large opening in the ring.

In Fig. 1 the aperture in the ring is shown as not truly cylindrical throughout its whole 45 length. The bottom portion is flared outwardly in a sort of conical configuration so that the casing may the more easily be placed in the ring or the ring placed over the end of the casing. The flaring at the 50 bottom of the ring does not materially reduce the strength of the elevator as the greatest stress, and therefore the greatest required strength, is at the top of the ring. In this case the making of the ring as heavy 55 at the bottom as at the top would be a mere waste of material and would increase the weight of the elevator without correspondingly increasing its strength.

A single bail 17 is secured to trunnions 18 60 on each side of the ring and extends upwardly to a sufficient height to allow of easy placement in the elevating hook, and also that the hook may clear the top of the casing collar when in its upright position. The trunnions are of such diameter that

their shearing strength is approximately equal to the tensile strength of the bail. It is desirable to have the trunnions slightly above the center of the ring as the elevator 70 then hangs normally in its correct upright position. At the same time, no large effort is required to turn the elevator out of its normal position as the center of gravity is only slightly below the point of support.

In Figs. 3 and 4 a second form of the elevator is shown in which there is provision for the gripping of the casing at points other than directly beneath the collars. The advantages of this particular form have been set forth hereinafter, the particular uses of 80 the same will be set forth after the following description of the mechanism thereof. In this form the ring is constructed in a slightly different configuration from that of the first form described, a pocket 20 being formed 85 therein for the reception of a slip or jaw 21 placed on a downwardly and inwardly sloping incline so that the weight of the casing upon the slip tends to tighten the grip of the elevator upon it. Bearing portion 9 and 90 the inner surface of the slip are both provided with teeth or other serrations or roughening to afford a thorough grip upon the casing.

In Fig. 5 a third form of the elevator is 95 shown, this form being a modification of the form shown in Fig. 3. In this last form the ring is made in a form differing from either of the ones described for the purpose of affording a frame for a plurality of slips 100 or jaws 21. These may be of any desired number, it being convenient for purposes of design to employ four as illustrated. In this form the gripping surfaces are all loose and free to move with the casing and to 105 consequently grip it on account of their inward motion. In the form of Fig. 3 there is one movable gripping surface and one which is stationary. It is conceivable that the form of Fig. 5 may be adapted to have 110 one or more of its gripping surfaces stationary, or that the form of Fig. 3 may be provided with a pair of movable jaws. These variations are cited for the purpose of showing some of the forms which the 115 present invention may take.

The peculiar and chief advantage of this elevator is seen to reside in the construction of the ring or body member in a single piece, in combination with a single bail.

The chief point of weakness in the elevators heretofore in use has been the jointed and hinged ring. To make these points of weakness sufficiently strong to stand the severe use to which they are subjected it is 120 necessary to make the elevators so heavy as to be unmanageable in the derrick. In the present elevator the elements of weakness are avoided with a construction sufficiently light to allow of extremely easy handling. 130

The use of the single bail is also of great utility as it allows of easier handling in the derrick. In the old construction it is necessary to put the two bails in their upright position and to slip the elevating hook through them at just the proper instant in its upward travel, the hook being so heavy that it must be thrust into the bails in its vertical position while hanging from the hoisting apparatus. In the present construction the single bail may be laid over on its side and into the hook at any time when the hook is sufficiently below the bail, the former difficulty of handling being thus obviated.

In the use of this elevator, as before explained, a spider is used on or below the derrick floor, this spider being of such construction as to grip the casing at any point along its length and to thus support it at any desired point. One or the other of the forms of the elevator is then used to raise and lower the casing, the spider being released when the elevator is supporting the casing. In the typical operation of placing the casing in the well, the elevator is placed over the end of a length of the casing which is then hoisted into the derrick. The lower end is placed in register with the casing already in the well and the two portions screwed together. In this relation the present elevator has a great advantage over the ones now used. When the joint is being screwed into the casing in the well, the old elevators are liable to turn with the casing. When this takes place the unbalanced weight of the elevator causes the casing to gyrate instead of remaining vertical. This causes the threads of the two portions to cross each other and it is thus impossible to form a good joint. It then becomes necessary to remove the elevator and to steady the joint by hand, the removal only being accomplished after some work in unfastening the catch and in swinging the halves of the elevator away from the casing. With the present form it is only necessary to lower the elevator slightly and to loosen the catch when it may be removed by hoisting. In the majority of cases it is not necessary to remove the present form as, when the catch is released, the size of the aperture through the ring is sufficient to allow the casing to turn without turning the elevator with it.

In the use of the form shown in the last figures it is not necessary that the casing be engaged at a point directly below the collar. Thus the casing may be held at any point while the other operations are carried on and it is possible to dispense with the spider entirely. In this case either two of the last forms may be used or one of the first and one of the last, just as conditions may require.

From the foregoing it will be manifest that the gist of this invention consists in

the employment of a ring which is put on the casing by slipping over the end, in combination with a mechanism for gripping the casing at some point, either directly below the collar or at any point along its length.

The minor details of construction, as to the particular means for engaging the casing, may be varied at will to suit the requirements without departing from the spirit and scope of this invention.

Having described my invention, what I claim is:—

1. A casing elevator, comprising a solid ring having an internal diameter larger than the external diameter of the casing, a collar, a catch member pivoted to one side of the ring at the top thereof and projecting inwardly into the internal opening of the ring, and locking means to prevent the displacement of the catch member.

2. A casing elevator, comprising a ring adapted to surround the casing, a catch member pivoted to one side of the ring at the top thereof and projecting inwardly into the internal opening of the ring, and locking means to prevent the displacement of the catch member.

3. A casing elevator, comprising a ring adapted to surround the casing, a bearing surface on the upper end of the ring at one side, a catch member pivoted to the upper end of the ring at the other side thereof and adapted to swing downwardly and inwardly into the interior opening of the ring to supply a bearing surface opposite the first named surface, a lock member mounted on the catch member, and a lug on the ring with which the lock member is adapted to engage.

4. A casing elevator, comprising a ring adapted to surround the casing, a bearing surface on one side of the interior upper edge of the ring, a catch member pivoted to the upper end of the ring at the other side thereof and adapted to swing downwardly and inwardly into the interior opening of the ring to supply a bearing surface opposite the first named surface, a lock member pivoted to the catch member, a lug on the ring adapted to engage the end of the lock member when the catch member is down, and a handle attached to the lug engaging end of the lock member.

5. A casing elevator, comprising a solid ring adapted to surround the casing and having a bearing surface on one side at its top for engagement with the casing collar, a catch member mounted on the other side thereof and projecting into the internal opening of the ring, its inner end forming a bearing for the casing collar on the side opposite that supported by the bearing surface on the ring, and lock means for securing the catch member in place against the casing.

6. A casing elevator, comprising a solid ring having an internal circular opening of larger diameter than the casing collar, a bearing surface formed on one side of the internal opening and on a radius approximately equal to that of the casing, the center of the bearing surface being non-coincident with the center of the internal opening, a catch member pivoted to the ring on the side opposite the bearing surface and projecting inwardly into the internal opening of the ring, and locking means to hold the catch member against the casing.

7. A casing elevator, comprising a solid ring having an internal circular opening of larger diameter than the casing collar, a bearing surface formed on one side of the internal opening and on a radius approximately equal to that of the casing, the cen-

ter of the bearing surface being non-coincident with the center of the internal opening, a catch member pivoted to the ring on the side opposite the bearing surface and projecting inwardly into the internal opening of the ring, a locking member pivoted to the catch member, a handle on the locking member, an abutment on the ring with which the locking member is adapted to engage, trunnions formed integrally with the ring, and a bail pivotally mounted on the trunnions.

In witness that I claim the foregoing I have hereunto subscribed my name this 11th day of December 1908.
